UNITED STATES PATENT OFFICE.

EDUARD PACHTMANN, OF DRESDEN, SAXONY, GERMANY.

PICTURE-HOLDER.

SPECIFICATION forming part of Letters Patent No. 375,189, dated December 20, 1887.

Application filed April 30, 1887. Serial No. 236,744. (No model.)

To all whom it may concern:

Be it known that I, EDUARD PACHTMANN, a subject of the King of Saxony, residing at the city of Dresden, Saxony, have invented a new and useful Improvement in Picture-Holders, of which the following is a clear and exact description of the same, reference being had to the accompanying drawings, forming a part of this specification.

The object of my invention is to produce a holder for photographs or other cards; and it consists of a novel device for holding the cards and for locking the cover of the same.

Referring to the drawings, Figure 1 is a side view of my improved picture-holder embodying my invention. Fig. 2 is a front view of the same. Fig. 3 is an enlarged front view of a modified form of the clasp. Fig. 4 is another modified form of the clasp. Fig. 5 is another modified form of the clasp.

A is the holder, consisting of the two side standards, $a' a'$, connected at the top by the cross piece d and at the bottom by the rest a^4 , which serves as a rest for the photographic leaves or cards a . The frame is further strengthened by the back plate or board, c . b is the cover, hinged at $x x$ to the side frames, $a' a'$. The photographic or other cards are introduced between the cover b and back plate, c . They rest loosely on the rest a^4 in the manner shown in Fig. 1.

The cover b is provided at the top with a clasp, e , consisting of two sliding bars, $e' e'$, acted upon by the spring e^2 . These bars at y enter sockets in the side frame, and are drawn inward by the knobs $e^5 e^6$.

By this arrangement the photographic leaves or cards $a a$ can be easily inserted or removed

for replacing other leaves or cards. The step-like arrangement of the rest a^4 permits this to be done. The steps of the rest a^4 can be of any shape that will produce the desired result.

In some cases I use the clasps f and g , (shown in Figs. 3 and 4,) which reach from the backing c to the cover b and fasten themselves between the knobs i .

I may also use the clasp H , as shown in Fig. 5, consisting of a tube, h , into which is inserted the screw-rod h^2 . The lower end of this rod h^2 is provided with disk h^3 , and is pressed between knobs $i i$. (See Fig. 5.) This device enables the clasp to be adjusted according to the capacity of the holder.

Having thus described my invention, I desire to claim—

1. In a picture-holder, the step-like rest a^4 , supported between the frame $a' a'$, in combination with the photographic leaves or cards a , substantially as set forth.

2. In a picture-holder, the clasp e , consisting of the rods $e' e'$ and spring e^2 , in combination with the cover b and side frames, $a' a'$, of the holder A , substantially as set forth.

3. In a picture-holder, the combination of the side frame, $a' a'$, held together by the cross-piece d , the back c , the step-like rest a^4 , the photographic leaves or cards $a a$, and the cover b , provided with clasp e , constructed as shown, all arranged substantially as set forth.

In witness whereof I hereunto set my hand 70 in presence of two witnesses.

EDUARD PACHTMANN.
